ART OF CRACKING HYDROCARBON OILS.

Application filed October 27, 1927. Serial No. 229,122.

This invention relates to improvements in the cracking of heavier and higher boiling hydrocarbon oils such as gas oil, fuel oil and topped crude oil, to produce therefrom lighter and lower boiling hydrocarbon oils, such as gasoline and gasoline-containing cracked distillates. The invention has several important advantages in heat economies, in features of control, in the treatment of particular stocks under particularly advantageous conditions, in obtaining a maximum yield and throughout with a minimum requirement of expensive apparatus designed to operate under high pressures and in the maintenance of conditions which permit prolongation of the useful period of operation without sacrifice of efficiency.

In carrying out the present invention, the oil to be cracked is forced in a single pass through a heating zone into a vaporizing zone being maintained under a super-atmospheric pressure in both the heating zone and the vaporizing zone. In the heating zone, the oil is heated to a cracking temperature by heat exchange with heating gases such as the hot products of combustion from a firebox in which fuel is burned. Unvaporized oil collecting in this vaporizing zone is withdrawn as a liquid therefrom and discharged into a separate vaporizing zone maintained under a pressure lower than that prevailing in the first. Vapors, including vapors of the desired lighter and lower boiling oils are separated in the first vaporizing zone and are taken off therefrom. Due to the reduction in pressure, a further separation of vapors is effected in the second vaporizing zone and these vapors are taken off and subjected to a refluxing operation to effect separation of the heavier fractions from the lighter fractions, which include constituents suitable as components of the desired gasoline-containing distillate, and intermediate refractory constituents that may advantageously be subjected to further cracking treatment. This refluxing operation is effected and controlled by passing fresh oil in heat exchanging relation with the cracked vapors, and reflux condensate so produced together with unvaporized constituents of the fresh oil are returned to the heating zone. Vapors escaping uncondensed from this re-

fluxing operation are condensed in a subsequent condensing operation.

The vapors taken off from the first vaporizing zone, the high pressure vaporizing zone, are subjected to a separate refluxing operation, which may advantageously be effected and controlled by the introduction of condensate of the vapors escaping uncondensed from the first mentioned refluxing operation. Vapors escaping from the second mentioned refluxing operation are condensed in a subsequent condensing operation as the desired gasoline-containing pressure distillate. Reflux condensate from the second mentioned refluxing operation together with the heavier unvaporized constituents introduced as components of the condensate of vapors escaping from the first mentioned refluxing operation are forced in a single pass through a separate heating zone into the second, low pressure, vaporizing zone, being heated to a cracking temperature in the second heating zone. Thus the introduction of condensate of the vapors escaping from the first mentioned refluxing operation may be regulated to control the second mentioned refluxing operation and at the same time to effect a redistillation of this condensate, as the lighter constituents contained in this condensate which are suitable as components of the desired pressure distillate product are vaporized and escape from the second mentioned refluxing operation together with the lighter vapors formed in the first or high pressure vaporizing zone.

The temperature to which the hot oil products are heated in the second heating zone and the pressure maintained thereon are advantageously somewhat higher than the temperature to which, and the pressure under which, the hot oil products are heated in the first heating zone. The hot products from the second heating zone are discharged directly to the second or low pressure vaporizing zone. The pressure under which the second heating zone is operated is maintained and controlled by a pressure regulating valve located in the discharge connection between the second heating zone and the second or low pressure vaporizing zone.

In one particularly advantageous method

practicing the process of the invention, reflux condensate from the refluxing operation to which the vapors from the high pressure vaporizing zone are subjected, is forced in a 5 single pass through a second heating zone and heated therein to a temperature sufficiently high to vaporize and crack the oil in the vapor phase. The hot oil products discharged into the low pressure vaporizing 10 zone from the second heating zone, if not already vaporized, are largely vaporized on reduction of pressure as discharged into the vaporizing zone and the heat contained in these hot oil products assists in vaporizing 15 an additional portion of the oil discharged directly into the low pressure vaporizing zone from the high pressure vaporizing zone. The unvaporized residue produced in the second vaporizing zone is not returned to 20 either heating zone but is discharged from the system.

Where desired a part of the fresh oil supplied to the system may be introduced directly to either of the heating zones. It is 25 advantageous to supply a lighter and more refractory oil to the second heating zone so that it will be subjected immediately to the more severe cracking conditions maintained therein and this lighter and more refractory 30 oil at the same time assists in preventing excessive carbon formation.

The first refluxing operation is advantageously effected under substantially the pressure prevailing in the first vaporizing zone; 35 the second refluxing operation is carried out under a lower pressure, that prevailing in the second vaporizing zone, or a lower pressure.

In carrying out the invention, it is advantageously to restrict the amount of vapors 40 taken off from the first vaporizing zone so that unvaporized constituents collect therein in the form of a freely flowing fluid residue. This restriction of the amount of vapors 45 taken off can be effected by regulating the pressure maintained in the first vaporizing zone, increasing the pressure to decrease the vaporization. It is also advantageous to maintain the unvaporized liquid oil constituents 50 in the first vaporizing zone for a substantial period of time. Vaporization in the second vaporizing zone may be carried far enough to leave a flux or heavy residue, which can be removed as a liquid, or it may 55 be carried so far that only coke or a coke mass remains. Vaporization in the second vaporizing zone also may be controlled by regulation of the pressure maintained therein. The vaporization in the second vaporizing zone is advantageously effected by the self-contained heat of the hot oil products 60 discharged thereinto from the first vaporizing zone and the second heating zone without further application of external heat. The first vaporizing zone may also be exter-

nally heated although a small amount of heat may be supplied externally if desired to secure a greater degree of vaporization.

Fig. 1 of the accompanying drawings illustrates pictorially the operation of the process of the invention. The invention will be fully described in connection with Fig. 2 of the accompanying drawings, which illustrate diagrammatically and conventionally one form of apparatus adapted for carrying 75 out the invention.

Referring to Fig. 2, the oil to be cracked is supplied from tank 1 by the pump 1^a. This oil may be introduced into the reflux tower 2 through connections 3, 4, and 5 or 80 it may be supplied directly to heating coil 6 through connections 3, 7, and 8, or it may be supplied directly to the heating coil 9 through connections 3, 4, 10, 11, and 12. The heating coil 6 discharges into the high 85 pressure vaporizing chamber 13 through connection 14. The heating coil 9 discharges into the low pressure vaporizing chamber 25 through connection 28 containing the pressure reducing valve 28^a. Vapors from the 90 high pressure vaporizing chamber 13 pass through connection 15 to the reflux tower 16. Vapors escaping from reflux tower 16 pass through connection 17 to condenser 18. Reflux condensate from reflux tower 16 95 passed to tank 19 through connection 20 and from thence is forced by the pump 22 through connections 23 and 12 to the heating coil 9, together with fresh oil supplied 100 through connection 11. Liquid residue collecting in the vaporizing chamber 13 is discharged through connection 24 containing the pressure-regulating valve 26 to the low pressure vaporizing chamber 25. The pressure-reducing valve 26 may be manually or 105 automatically controlled, for example, it may be arranged to operate to maintain a fixed liquid level in the high pressure vaporizing chamber 13. Where the vaporization in the low pressure vaporizing chamber 25 is carried to the point where coke or a coky mass remains, duplicate vaporizing receptacles may be provided so that the operation may be carried out in a continuous manner. Vapors from the low pressure vaporizing chamber 25 pass through connection 27 to the reflux tower 2, and vapors remaining uncondensed escape from the reflux tower 2 through connection 29 to condenser 30. Reflux condensate from reflux tower 2, together with unvaporized oil supplied to tower 2 through connection 5, pass through connection 31 to tank 32. Reflux condensate from this tank passes through connections 33 and 8 and by means of pump 34 is reintroduced into the heating coil 6. Condensers 18 and 30 discharge into the receivers 35 and 36 respectively. The condensate from receiver 35 may be separately discharged through connection 37 to the tank 38 and 110

115 vapors from the low pressure vaporizing chamber 25 pass through connection 27 to the reflux tower 2, and vapors remaining uncondensed escape from the reflux tower 2 through connection 29 to condenser 30. Reflux condensate from reflux tower 2, together with unvaporized oil supplied to tower 2 through connection 5, pass through connection 31 to tank 32. Reflux condensate from this tank passes through connections 33 and 8 and by means of pump 34 is reintroduced into the heating coil 6. Condensers 18 and 30 discharge into the receivers 35 and 36 respectively. The condensate from receiver 35 may be separately discharged through connection 37 to the tank 38 and 120 125 130

the condensate from receiver 36 discharged to the tank 39, or both condensates or a part of both condensates may be collected in tank 40 and the composite condensate so produced supplied to reflux tower 16 by the pump 41 through connection 42. The pressure in the high pressure vaporizing chamber may be maintained and regulated by means of the valve 43 in connection 17 between the reflux tower 16 and the condenser 18. The condenser 18 may be operated at atmospheric pressure or at substantially the same pressure prevailing in the reflux tower 16, superatmospheric pressure being maintained therein by means of valve 44 or by means of valves 45 and 46. Superatmospheric pressure may be maintained in the low pressure vaporizing chamber, or the pressure therein regulated, by means of valve 47 or 48, or by means of suitable valves beyond the condenser. Liquid residue may be discharged from the low pressure vaporizing chamber 25 through connection 49 controlled by valve 50. In the receivers 35 and 36 the condensed product is separated from any gases or vapors remaining uncondensed and the gases and vapors discharged through connections 51 and 52 respectively.

The heating coils 6 and 9 are arranged in separate heating furnaces 53 and 54 respectively. These furnaces comprise a fire box, heating flues in which the heating coils are arranged, and a stack flue through which waste heating gases escape from the heating flues. Means may be provided, as shown at 55 and 56, for recirculating through the heating flues with fresh hot products of combustion from the fire box, a portion of the escaping waste heating gases. The provision of separate heating furnaces makes possible the separate and independent regulation and control of the heating operations carried out in the two heating coils. Additional heat may be supplied to the high pressure vaporizing chamber 13 by means of the furnace 57, or this chamber may be externally unheated. The low pressure vaporizing chamber 25 and connection 24 between the high pressure vaporizing chamber and the low pressure vaporizing chamber are thoroughly lagged or heat-insulated to prevent heat loss. The high pressure vaporizing chamber, particularly where externally unheated, may also be lagged or heat-insulated in a similar manner. It is also advantageous to thoroughly lag or heat-insulate the connections 14 and 28 from the heating coils to the vaporizing chambers, and the return connections from the reflux towers 2 and 16 including the tanks 19 and 32 to further conserve heat.

In operation, liquid residue may be discharged from the high pressure vaporizing chamber 13 to the low pressure vaporizing chamber 25 at a rate, for example, about 80

to 85% of the rate at which raw fresh oil is supplied to the system, and about 35 to 40% of the rate at which oil is introduced to the high pressure vaporizing chamber. A large portion of this residue will be vaporized in the low pressure vaporizing chamber by reason of the reduced pressure prevailing therein and the additional heat contained in the hot oil products discharged from the heating coil 9. The residue remaining unvaporized in the low pressure vaporizing chamber and withdrawn therefrom as a liquid will normally amount to less than 35 to 40% of the residue discharged from the high pressure vaporizing chamber and about 80 to 35% of the fresh oil charged to the system.

The high pressure vaporizing chamber may be operated, for example, at pressures of 100 to 150 pounds per square inch or at higher pressures, and the low pressure vaporizing chamber may be operated, for example, at pressures ranging from atmospheric pressure or somewhat lower pressures up to about 50 pounds per square inch, or somewhat higher.

The second heating zone may advantageously be operated at pressures of 150 to 200 pounds per square inch or at higher pressures. Vaporization in the low pressure vaporizing chamber may be promoted by the introduction of steam. The hot oil products may be discharged from the heating coil 6 at a temperature of about 750 to 800° F. The operation may with advantage be conducted so as to discharge the hot oil products from the heating coil 9 substantially in the vapor state at a temperature of about 900 to 950° F. While additional raw oil may be introduced to either of the heating coils directly, it is advantageous to introduce all, or substantially all, of the raw oil to reflux tower 2 to effect the control and refluxing operation. Introducing all or substantially all of the raw oil to the refluxing operation in this manner has the further advantage that the fresh oil is preheated and may also, to a certain extent, be fractionally distilled, so that the heavier and lighter portions are separated and subsequently subjected to conditions most advantageous for the cracking of those particular components.

The invention may be further illustrated by the following more specific example of an operation in accordance with the invention as carried out to produce gasoline-containing cracked distillate from a gas oil character charging stock, in an apparatus of the type illustrated. The heating furnace 53 is operated to maintain a discharge temperature from the heating coil 6 of about 750 to 800° F. and the heating furnace 54 to maintain a discharge temperature from the heating coil 9 of about 900 to 950° F. tower 16 is maintained in the neighborhood of 400° F. and the head temperature of the reflux tower 2 in the neighborhood of 525° F. The high pressure vaporizing chamber 13 is operated under a pressure of about 100 pounds per square inch, this pressure being maintained through the reflux tower 16 and reduced and regulated by means of the valve 43 between the reflux tower and the condenser. The heating coil 9 is operated under a pressure of about 200 pounds per square inch, this pressure being maintained and regulated by means of the valve 28^a in connection 28. The low pressure vaporizing chamber 25 and the reflux tower 2 are operated under substantially atmospheric pressure. Raw oil, 31° Baumé gas oil, is supplied at a rate of about 2000 gallons per hour and at a temperature of about 80° F.; about 1600 gallons per hour of raw oil being introduced into the reflux tower 2 through connection 5, and about 200 gallons per hour of raw oil being supplied directly to the heating coil 6 through connection 7, and about 200 gallons per hour of raw oil being supplied directly to the heating coil 9 through connections 10 and 11. Vapors pass from the high pressure vaporizing chamber 13 to the reflux tower 16 at a temperature of about 710° F. and at a rate of about 2600 gallons per hour. Liquid residue is discharged from the high pressure vaporizing chamber 13 to the low pressure vaporizing chamber 25 at a temperature of about 700° F. and at a rate of about 1650 gallons per hour. Reflux condensate is withdrawn from reflux tower 16 at a temperature of about 490° F. and at a rate of about 2940 gallons per hour. The reflux condensate fresh oil mixture from reflux tower 16 and connection 11, is supplied to the heating coil 9 at a temperature of about 460° F. at a rate of about 3140 gallons per hour. The vapor mixture discharged from the low pressure vaporizing chamber is passed to the reflux tower 2 at a temperature of about 790° F. and at a rate of about 4150 gallons per hour. Liquid residue having a gravity of about 12° Baumé is withdrawn from the low pressure vaporizing chamber at a temperature of about 780° F. and at a rate of about 640 gallons per hour. The mixture of reflux condensate and pre-heated fresh oil is withdrawn as a liquid from reflux tower 2 at a temperature of about 575° F. and at a rate of about 4050 gallons per hour, and the composite reflux and fresh oil mixture including the raw oil supplied through connection 7 is passed to the heating coil 6 at a temperature of about 550° F. and at a rate of about 4250 gallons per hour. Vapors are withdrawn from reflux tower 2 at a temperature of about 525° F. at a rate of about 1700 gallons per hour and the distillate produced by subsequent

condensation of these vapors is introduced to reflux tower 16 to effect and control the refluxing operation therein. Vapors are taken off from reflux tower 16 at a temperature of about 400° F. at a rate of about 1360 70 gallons per hour. The distillate produced by condensation of these vapors has a gravity of about 51° Baumé. Where references to volumes per hour of vapors or vapor mixtures have been given in the foregoing example, it is to be understood that the amounts given are in terms of the amount of liquid equivalent to the amount of vapor or vapor mixture. It will also be understood that the volumes per hour, gravities and 80 temperatures given in the foregoing example are given only as representative of approximate averages.

By recycling the oil, separating as vapors in the low pressure vaporizing chamber 85 from the liquid residue discharged from the high pressure vaporizing chamber, the present invention makes it possible to discharge from the high pressure vaporizing chamber a larger proportion of the oil entering the 90 high pressure vaporizing chamber from the heating coil as a liquid residue without again subjecting the unvaporized oil to a heating operation in which heat is applied to the oil externally and without interfering with the efficiency of the operation or the capacity of the apparatus. Also by separating in reflux tower 2 vapors liberated at the reduced pressure prevailing in the 95 low pressure vaporizing chamber and returning the heavier and less refractory portions to the heating zone maintained at the lowest temperature, and by further separating the products escaping as vapors from this reflux tower in the reflux tower 16, as 100 described, the lighter constituents formed by the cracking operation in the heating coil 9 are permitted to escape without being again subjected to a cracking temperature so that 105 over-cracking is avoided while the lighter intermediate constituents uncondensed in reflux tower 2 but condensable at the temperature maintained in reflux tower 16 are subjected to a more severe cracking operation together with the condensate of similar 110 nature which vaporizes even at the high pressure prevailing in the high pressure vaporizing chamber, while substantially none of the heavier constituents such as may be 115 contained in the fresh oil and heavier condensate of vapors liberated under conditions of cracking temperature and reduced pressure are ever subjected to the more severe cracking temperature maintained in the heating zone 9. It will be apparent that 120 the selective treatment of condensates of vapors from the low pressure vaporizing chamber permits an increased yield to be obtained while at the same time eliminating 125 or greatly reducing both the tendency to 130

over-cracking and the excessive formation of coky materials. These conditions also cooperate in a particularly advantageous manner to greatly prolong the useful period of operation. It is a further advantage of the process of the invention that notwithstanding the increased yields and large capacity which may be obtained, only one vaporizing chamber is required which need be of the 10 expensive construction necessary to withstand high pressures at high temperatures.

We claim:

1. An improved method of cracking hydrocarbon oils which comprises forcing raw oil in a single pass through a heating zone into a vaporizing zone and maintaining the oil under superatmospheric pressure in both the heating zone and the vaporizing zone, heating the oil to the cracking temperature 20 in the said heating zone, subjecting the vapors from the said vaporizing zone to a refluxing operation, passing unvaporized oil from the said vaporizing zone to a second vaporizing zone and maintaining the oil 25 therein under a pressure lower than that prevailing in the first vaporizing zone, subjecting vapors from the second vaporizing zone to a separate refluxing operation and forcing reflux condensate therefrom in a 30 single pass through the said heating zone in admixture with raw oil, passing reflux condensate from the said first mentioned refluxing operation in a single pass through a separate heating zone and heating the oil 35 to a cracking temperature therein, maintaining superatmospheric pressure on the second mentioned heating zone at least as high as that maintained on the first mentioned vaporizing zone, discharging the hot 40 oil products from the second mentioned heating operation directly to the second mentioned vaporizing zone and taking off vapors from both refluxing operations.

2. An improved method of cracking hydrocarbon oils which comprises forcing raw oil in a single pass through a heating zone into a vaporizing zone and maintaining the oil under superatmospheric pressure in both the heating zone and the vaporizing zone, heating the oil to the cracking temperature in the said heating zone, subjecting the vapors from the said vaporizing zone to a refluxing operation, passing unvaporized oil from the said vaporizing zone to a second 55 vaporizing zone and maintaining the oil therein under a pressure lower than that prevailing in the first vaporizing zone, subjecting vapors from the second vaporizing zone to a separate refluxing operation effected by heat exchange with raw oil and forcing the reflux condensate therefrom in admixture with the raw oil preheated thereby in a single pass through the said heating zone, passing reflux condensate from 60 the said first mentioned refluxing operation

in a single pass through a separate heating zone and heating the oil to a cracking temperature therein, maintaining superatmospheric pressure on the second mentioned heating zone at least as high as that maintained on the first mentioned vaporizing zone, discharging the hot oil products from the second mentioned heating operation directly to the second mentioned vaporizing zone and taking off vapors from both refluxing operations.

3. An improved method of cracking hydrocarbon oils which comprises forcing raw oil in a single pass through a heating zone into a vaporizing zone and maintaining the oil under superatmospheric pressure in both the heating zone and the vaporizing zone, heating the oil to the cracking temperature in the said heating zone, subjecting the vapors from the said vaporizing zone to a refluxing operation, passing unvaporized oil from the said vaporizing zone to a second vaporizing zone and maintaining the oil therein under a pressure lower than that prevailing in the first vaporizing zone, subjecting vapors from the second vaporizing zone to a separate refluxing operation and introducing reflux condensate therefrom to the said heating zone in admixture with the raw oil, passing reflux condensate from the said first mentioned refluxing operation in a single pass through a separate heating zone and heating the oil to a higher cracking temperature in the said separate heating zone than the temperature to which the oil is heated in the first mentioned heating zone, maintaining superatmospheric pressure on the second mentioned heating zone, discharging the hot oil products from the second mentioned heating operation directly to the second mentioned vaporizing zone and taking off vapors from both refluxing operations.

4. An improved method of cracking hydrocarbon oils, which comprises forcing raw oil in a single pass through a heating zone into a vaporizing zone and maintaining the oil under superatmospheric pressure in both the heating zone and the vaporizing zone, heating the oil to the cracking temperature in the said heating zone, subjecting the vapors from the said vaporizing zone to a refluxing operation, passing unvaporized oil from the said vaporizing zone to a second vaporizing zone and maintaining the oil therein under a pressure lower than that prevailing in the first vaporizing zone, subjecting vapors from the second vaporizing zone to a separate refluxing operation and introducing reflux condensate therefrom to the said heating zone in admixture with the raw oil, passing reflux condensate from the said first mentioned refluxing operation in a single pass through a separate heating zone and heating the oil to a cracking tem-

perature therein, maintaining a superatmospheric pressure on the said separate heating zone in excess of the pressure maintained on the first mentioned heating zone, discharging the hot oil products from the second mentioned heating operation directly to the second mentioned vaporizing zone, and taking off vapors from both refluxing operations.

10 5. An improved method of cracking hydrocarbon oils, which comprises forcing raw oil in a single pass through a heating zone into a vaporizing zone and maintaining the oil under superatmospheric pressure in both 15 the heating zone and the vaporizing zone, heating the oil to the cracking temperature in the said heating zone, subjecting the vapors from the said vaporizing zone to a refluxing operation, passing unvaporized 20 oil from the said vaporizing zone to a second vaporizing zone and maintaining the oil therein under a pressure lower than that prevailing in the first vaporizing zone, subjecting vapors from the second vaporizing 25 zone to a separate refluxing operation and introducing reflux condensate therefrom to the said heating zone in admixture with the raw oil, passing reflux condensate from the said first mentioned refluxing operation in 30 a single pass through a separate heating zone and heating the oil therein to vaporize and crack the oil in the vapor phase, discharging the hot vapors from the said separate heating zone directly to the second mentioned vaporizing zone and taking off 35 vapors from both refluxing operations.

6. An improved method of cracking hydrocarbon oils, which comprises forcing raw oil in a single pass through a heating zone into a vaporizing zone and maintaining the oil under superatmospheric pressure in both 40 the heating zone and the vaporizing zone, heating the oil to the cracking temperature in the said heating zone, subjecting the 45 vapors from the said vaporizing zone to a refluxing operation, passing unvaporized oil from the said vaporizing zone to a second vaporizing zone and maintaining the oil therein under a pressure lower than that 50 prevailing in the first vaporizing zone, subjecting vapors from the second vaporizing zone to a separate refluxing operation and introducing reflux condensate therefrom to the said heating zone in admixture with the 55 raw oil, passing reflux condensate from the said first mentioned refluxing operation in a single pass through a separate heating zone and heating the oil to a cracking temperature therein, maintaining superatmospheric 60 pressure on the second mentioned heating zone at least as high as that maintained on the first mentioned vaporizing zone, discharging the hot oil products from the second mentioned heating operation directly

to the second mentioned vaporizing zone, taking off vapors from both refluxing operations and condensing the vapors, and introducing condensate of vapors escaping from the second mentioned refluxing operation to the first mentioned refluxing operation.

7. An improved method of cracking hydrocarbon oils, which comprises forcing raw oil in a single pass through a heating zone into a vaporizing zone and maintaining the oil under superatmospheric pressure in both 75 the heating zone and the vaporizing zone, heating the oil to the cracking temperature in the said heating zone, subjecting the vapors from the said vaporizing zone to a refluxing operation, passing unvaporized oil 80 from the said vaporizing zone to a second vaporizing zone and maintaining the oil therein under a pressure lower than that prevailing in the first vaporizing zone, subjecting vapors from the second vaporizing zone to a separate refluxing operation effected by heat exchange with raw oil and introducing the reflux condensate therefrom in admixture with the raw oil preheated thereby to the said heating zone, passing reflux condensate from the said first mentioned refluxing operation in a single pass through a separate heating zone, maintaining superatmospheric pressure in the said separate heating zone and heating the oil therein to a higher cracking temperature than the temperature to which the oil is heated in the first mentioned heating zone, discharging the hot oil products from the said separate heating zone directly to the second mentioned 90 vaporizing zone, taking off vapors from both refluxing operations and condensing the vapors, introducing condensate of vapors escaping from the second mentioned refluxing operation, and discharging unvaporized residue from the second mentioned vaporizing zone.

8. An improved method of cracking hydrocarbon oils, which comprises forcing oil in a single pass through a heating zone into a vaporizing zone and maintaining the oil under superatmospheric pressure in both 100 the heating zone and the vaporizing zone, heating the oil to the cracking temperature in the said heating zone, subjecting vapors from the said vaporizing zone to a refluxing operation, passing unvaporized oil from the said vaporizing zone to a second vaporizing zone and maintaining the oil therein under a pressure lower than that prevailing in the first vaporizing zone, subjecting the vapors from the second vaporizing zone to a separate refluxing operation, introducing raw oil to the separate refluxing operation, and supplying reflux condensate and 110 admixed unvaporized oil together with an independent supply of raw oil to the said heating zone, passing reflux condensate from 115

the said first mentioned refluxing operation in a single pass through a separate heating zone and heating the oil therein to a higher cracking temperature in the said separate heating zone than the temperature to which the oil is heated in the first mentioned heating zone, discharging the hot oil products from the second mentioned heating opera-

tion directly to the second mentioned vaporizing zone and taking off vapors from both refluxing operations.
